UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,689, dated January 6, 1885.

Application filed November 15, 1884. Term of patent 24 years.

To all whom it may concern:

Be it known that I, MARY TURNER, of the city, county, and State of New York, have invented and produced a new and original 5 Design for a Pattern of a Lady's Costume, (numbered 9,518;) and I do hereby declare that the engraved prints accompanying this specification convey to any one accustomed to using paper patterns a clear understanding of how 10 a garment made up by the pattern will appear.

The design shows a round walking-skirt and a basque. The skirt exhibits a full front drapery that falls in a point almost to the bottom of the center of the front, and displays 15 draping plaits in its right back edge; a deep side-plaited panel at the left side that appears to overlap the front drapery more than half way down; a full back drapery that falls 20 deeper at the left side than at the right, and displays draping plaits in its front edges and

loopings at the center, and a side plaiting that appears to trim that part of the skirt not covered by the panel and draperies. The basque exhibits closely-fitted fronts that arch 25 high over the hips and appear to be separated at their front edges by a narrow pointed vest, a closely-fitted back that is deep and square, and exhibits an opening at the center of its skirt, and an under-folded plait at the lower 30 part of each side back seam, coat-sleeve, and a standing collar.

What I claim as my invention, and desire to secure by Letters Patent, is—

The design for a lady's costume, as shown 35 in the engraved prints accompanying this specification.

MARY TURNER.
